[57] CLAIM

The ornamental design for a survey response terminal, as shown and described.

DESCRIPTION

FIG. 1 is a top, front, right side perspective view of a survey response terminal showing our new design; FIG. 2 is a top plan view thereof; FIG. 3 is a right side elevational view thereof; FIG. 4 is a rear elevational view thereof; FIG. 5 is a front elevational view thereof; FIG. 6 is a left side elevational view thereof; FIG. 7 is a bottom plan view thereof.

The numerals and words are shown on the keys in FIGS. 1 and 2 in broken lines for illustrative purposes only and thus form no part of the claimed design.
